UNITED STATES PATENT OFFICE.

CHARLES L. PRUDEN, OF NEW YORK, N. Y.

WATER-HAMMOCK.

SPECIFICATION forming part of Letters Patent No. 689,020, dated December 17, 1901.

Application filed September 28, 1901. Serial No. 76,845. (No model.)

To all whom it may concern:

Be it known that I, CHARLES L. PRUDEN, a subject of the King of Great Britain, and a resident of New York, in the county of Kings 5 and State of New York, have invented certain new and useful Improvements in Water-Hammocks, of which the following is a specification, taken in connection with the accompanying drawings, annexed to and forming part of 10 the same.

This invention relates to water-hammocks which may be used for life-saving or for bathing purposes.

In the accompanying drawings, in which the 15 same reference character refers to similar parts in the various views, Figure 1 is a top view of one form of this invention. Fig. 2 is a side sectional view of the same. Fig. 3 is a top view of a modified form of this device.

20 In the form of water-hammock shown in Figs. 1 and 2 the side pieces A, preferably of wood, are rigidly secured to the transverse members B and B² to form a rigid frame. The floats C are formed of papier-mâché or 25 of metal suitably protected from the action of the water or, if desired, of rubber, so as to form an air-tight float. The edges of the material of which the float is composed are clamped together by the clamping members 30 A' and B', which serve to make the floats airtight and also to secure them to the frame. In this way the floats remain filled with air, and since they are properly protected by painting them or otherwise they possess great 35 buoyancy and prevent the frame from being submerged. It is understood, of course, that, if desired, the floats may be formed by filling them with cork or any other desired light substance.

40 The cradle D, which is secured to the frame, is formed of the longitudinal strips of textile material D² and the transverse strips D', which are secured together at each point of intersection, so that the whole forms a meshed textile fabric. The meshes of this cradle may 45 be made of any size desired, and, indeed, this cradle may, if desired, be made of the netted fabric formed of twine or similar material.

The cradle is secured to the side pieces A and also to the transverse supporting-pieces B², so 50 that the cradle in whichever position the hammock may be placed upon the water is always free to assume a position below the frame of the hammock, so that if the frame is turned over the cradle can easily assume 55 the position indicated in dotted lines in Fig. 2. The two strips D³, of textile material or any other desired material, are secured above the floats and assist in holding them in proper position and also form a ready means of 60 grasping the hammock.

In the use of this device in life-saving or in bathing the hammock is thrown upon the water and floats in the position indicated in Fig. 2. A person or number of persons resting within the cradle are supported by the floats and by the buoyancy of the frame of the hammock; but it will be noticed that since in this position they are largely submerged the water-hammock can support a 70 much greater load under these conditions than if the persons upon it were entirely out of the water, so that their whole weight would necessarily be upheld by the buoyancy of the device. The form of the water-hammock is very convenient, since persons may 75 readily be supported by it as they cling to the frame or to the cradle without being supported in the cradle.

80 In the multiple form of water-hammock shown in Fig. 3 the frame is built up of a number of longitudinal members E, forming, together with the transverse members F, a rigid frame. The floats G are arranged within the frame, as indicated, and serve in connection 85 with the material of which the frame is made, which is usually some light wood, to give the requisite buoyancy. The cradles H, which may be formed of strips of fabric or of netted fabric, are secured within each of the compartments of the frame and act in a manner 90 similar to the simple form of water-hammock which has been described.

95 It is manifest that many modifications may be made in this device by those familiar with the art without departing from the spirit of

this invention. I do not therefore wish to be limited to the exact disclosure which I have made in this case; but

What I wish to secure by Letters Patent is set forth in the appended claim:

In a water-hammock, a rigid frame composed of side pieces and transverse pieces, floats secured at either end of the frame by clamping members secured to the side pieces

and transverse pieces, said floats being of air-tight cellular structure and a cradle of textile meshed structure secured to said frame between said floats to assume a position below said frame.

CHARLES L. PRUDEN.
